HENRY G. DYER, OF COLLINGSWOOD, NEW JERSEY, ASSIGNOR TO VINCENT M. STEVENSON, OF PHILADELPHIA COUNTY, PENNSYLVANIA.

FLAMING-ARC ATTACHMENT FOR INCLOSED-ARC LAMPS.

1,101,014.

Specification of Letters Patent. **Patented June 23, 1914.**

Continuation in part of application Serial No. 742,643, filed January 17, 1913. This application filed July 5, 1913. Serial No. 777,458.

To all whom it may concern:

Be it known that I, HENRY G. DYER, a citizen of the United States, residing at Collingswood, in the county of Camden and 5 State of New Jersey, have invented a certain new and useful Flaming-Arc Attachment for Inclosed-Arc Lamps, of which the following is a specification, the present case being a continuation in part of my application 10 for Letters Patent filed January 17, 1913, and Serial No. 742,643.

The principal objects of the present invention are first, to provide, as a new article of manufacture, an attachment complete 15 in itself, which is adapted for detachable connection to any of the well-known types of so called inclosed arc lamps now in use, whereby any of such arc lamps without change of construction of its parts may be 20 converted into a flaming arc lamp at comparatively small cost; second, to provide such an attachment consisting primarily of a translucent arc inclosing chamber and a separable condensing chamber, the bottom 25 of which is of translucent material and the continuous top of which is of opaque material; third, to provide such an attachment designed to prevent rays of light being diffused from the condensing chamber top but 30 calculated to permit rays of light being diffused from the condensing chamber bottom and from the arc inclosing chamber over a relatively large space.

Other and further objects of the invention 35 relate to the providing of general details of construction and arrangement and combination of parts as will hereinafter more fully appear.

With these objects in view the invention 40 consists of the improvements hereinafter described and finally claimed.

The nature, characteristic features and scope of the invention will be more fully understood from the following description 45 taken in connection with the accompanying drawings forming part thereof, and in which:

Figure 1, is a view in central section of the attachment embodying the invention. 50 Fig. 2, is a top or plan view thereof, drawn upon a reduced scale, Fig. 3, is a view partly in elevation, and partly in central section, of the attachment of the invention, illustrating the position of the same for lamp

cleaning and trimming purposes, and Fig. 55 4, is a view in section taken upon the line 4—4 of Fig. 3.

Referring to the drawings, there is disclosed a physical embodiment of the invention, the same being constructed in accordance 60 with the mode best known to me at this time for practising the invention. Obviously, various details of construction and arrangement of parts may be substituted without departing from the spirit of the 65 invention and I wish it understood that I consider mere changing of details as coming within the scope of the present invention.

The present attachment is so designed 70 that it may, at small cost, be readily and expeditiously attached to any type of the so called inclosed arc lamps now in use without reconstruction of the lamp parts, whereby the same may be converted into a flaming 75 arc lamp. Thus by the use of such attachment an inclosed arc lamp, may if desired, be interchangeably used as an arc lamp or a flaming arc lamp, thereby enhancing the efficiency and commercial value 80 of the same.

The attachment of the invention is complete in its self and constitutes a new article of manufacture. It consists primarily of a translucent arc inclosing chamber A, 85 and a two-part, separable condensing chamber B, the bottom of which condensing chamber is of translucent material, and the top of which is of opaque material. The top of the two part condensing chamber in 90 practice is preferably formed of metal and consists of a continuous dome-shaped structure 10, centrally apertured for a purpose to be presently described. As clearly shown in Fig. 2, the dome 10, considered in plan 95

is of circular configuration and is provided with an annular flanged portion 11, terminating in a depending rim 12. The flanged portion 11, of the dome 10, has secured upon its under side a packing ring 100 or gasket 13, of asbestos or the like. To complete the two-part condensing chamber B, use is made in practice of glassware C, also of circular configuration in plan, which glassware forms the condensing chamber 105 bottom and has preferably formed integral therewith and centrally depending therefrom an open top bulb-like structure D con-

stituting the arc inclosing chamber A. As clearly shown in Fig. 3, the rim of the glass-ware C is removably seated upon the flanged portion 14 of a metallic ring 15, which 5 flanged portion is provided with a packing ring or gasket 16, of asbestos or the like. The ring 15, is arranged to fit snugly within the rim 12, of the dome piece 10, and the upper edges of the ring 15, and glassware C 10 are held in abutting position with the under- side of the ring 13, by means of suitable clamping mediums, shown in the drawing as being pivotal catches 17. The parts thus clamped together form a relatively air tight 15 structure.

Within the condensing chamber B, and secured to the dome 10, as by screws 18, is a generally cylindrical member 19 which is in practice made in one piece and pro- 20 trudes downward into the open top of the bulb-like structure D, as clearly shown in Fig. 1. The outside diameter of that part of the member 19, which extends into the bulb-like structure is of a diameter slightly 25 smaller than the inside diameter of said structure at that point, so that a small annular space F, is present between said parts, see Fig. 1. From the bottom of the member 19, to within a short distance of the top 30 of said member the walls thereof are solid. Immediately adjacent the dome top, how- ever, the walls of the member 19 are slotted as at 21, for a purpose to be presently de- 35 scribed.

Fitted between the dome 10 and the top 35 of the member 19, is the flanged portion of an inverted cone frustum shaped gas diverter 22, the body of which extends through the open top of the member 19, well within 40 the same, and to a point below the slotted walls 21. This gas diverter 22, is of insulating material and as shown closes the open top of the member 19. It is also formed at its top to penetrate the central 45 opening in the dome 10, and is centrally apertured for the passage therethrough of an upper electrode.

Depending from lugs 23, carried by the member 19, are rods 24, which support a 50 carbon holder 25. As shown the carbon holder 25, extends to within a short distance of the closed bottom of the arc inclos- ing chamber A.

Fixed exteriorly upon the dome 10, is 55 a generally dish-shaped supporting attachment 26, having an annular flanged portion 27. Fitted over the dish-shaped part 26, is a top plate 28, centrally apertured to ac- 60 commodate an upper electrode. This plate 28, is removably attached as clearly shown in Fig. 2. As shown the plate 28, margin- 65 ally considered, is provided with a series of slots 29, communicating with relatively large apertures 30. Screws 31, pass through the slotted portions of the plate 28, and en-

gage the flange 27, of the dish-shaped mem- 70 ber 26. By this construction, the plate 28, may be readily removed by unloosening the screws 31, and partially rotating the plate 28, to the right in Fig. 2, until the apertures 30, registered with the head of the screws 31, whereupon the plate 28, may be readily removed.

To apply the above described attachment to an inclosed arc lamp it is merely neces- 75 sary to remove from the body of the arc lamp its globe and lower carbon holder. The top plate 28, of the present attachment is then suitably drilled to accommodate screws for securing the same to the body 80 of the arc lamp and when the top plate has been made fast the attachment is secured to said top plate by passing the heads of the screws 31, through the apertures, 30, and slightly rotating the attachment to the left 85 in Fig. 2, at which time the screws 31, are secured to place. In operation, the vapors, gases and smoke given off by the electrodes are caused by the heat of the arc to pass up- 90 wardly through the generally contracted bulb-like structure D, and quickly ascend through the opening 20, in the member 19, and pass out into the condensing chamber through the slots 21, the part 22, serving to divert or spread the vapor, gases and smoke 95 toward said slots in this upward movement. Thus the quick ascension of the vapors, gases and smoke serves to reduce gaseous condensation deposits upon the bulb-like structure forming the arc inclosing cham- 100 ber. The vapors, gases and smoke leave the member 19, immediately adjacent the top of the condensing chamber and circulate therearound in a continuous cycle, until con- 105 densation occurs. As the metallic dome 10, by reason of the specific construction shown is relatively cooler than is the annular dish- shaped bottom of the condensing chamber, rapid condensation is effected and condensa- 110 tion products accumulate both upon the dome 10, and upon the dished portion of the condensation chamber bottom. Thus, dur- 115 ing the circulation of the combustion products within the chamber B, the gases return- ing to the arc inclosing chamber are sub- stantially free from condensable products and the generally curved part 32, of the member 19, coöperates with the small an- 120 nular space F, to baffle and prevent their return. It may be stated at this time, that the part 19, further serves to prevent to a great degree rays of light finding their way 125 to the condensation chamber, and those rays of light which do reach the condensing chamber are reflected by the dome piece 10, and diffused through the glass bottom C, even though condensation deposits are present thereon. It may be further stated that with deposits of condensation upon the dish shaped condensation chamber bottom addi- 130

tional reflection of light is provided for as rays of light impinge thereon from the light transmitting part of the attachment.

The dome 10, and ring 15, are connected together by short chain sections 34, so that, when it is desired to clean the attachment parts, or trim the lamp, the pivotal clips 17, are unfastened, so that the ring 15, together with the glassware may conveniently be dropped to the position shown in Fig. 3.

What I claim is:—

1. In an attachment of the class described, a separable condensing chamber the top of which consists of a continuous dome-like opaque structure apertured centrally thereof and the bottom of which consists of an annular translucent structure terminating in a depending, central bulbous arc inclosing chamber, and means for detachably coupling together the condensing chamber parts.

2. In an attachment of the class described, a separable condensing chamber the top of which consists of a continuous dome-like opaque supporting structure apertured approximately centrally thereof and the bottom of which consists of an annular dished translucent structure terminating in a depending, central bulbous arc inclosing chamber and means for detachably coupling together the condensing chamber parts.

3. In an attachment of the class described, a separable condensing chamber the top of which consists of a continuous dome-like opaque centrally apertured supporting structure and the bottom of which consists of an annular translucent structure terminating in a depending, central bulbous arc inclosing chamber, a centrally disposed member suspended within the condensing chamber the bottom thereof extending into the arc inclosing chamber said member having a passage therethrough for directing combustion products to the condensing chamber top, and means for detachably coupling together the condensing chamber parts.

4. In an attachment of the class described, a separable condensing chamber the top of which consists of a dome-like metallic centrally apertured supporting structure and the bottom of which consists of an annular member of glass terminating in a depending central bulbous arc inclosing chamber, a centrally disposed generally cylindrical member suspended within the condensing chamber the bottom thereof extending into the arc inclosing chamber said member being provided with openings adjacent its top and a passage therethrough for directing combustion products to the condensing chamber, a diverter of inverted cone-frustum shape projected into the said member for deflecting outwardly combustion prod-

ucts through said openings to the condensing chamber top and means for detachably coupling together the condensing chamber parts.

5. In an attachment of the class described, a separable condensing chamber the top of which consists of a continuous dome-like metallic supporting structure, centrally apertured, and the bottom of which consists of an annular dished member of glass terminating in a central depending bulbous arc inclosing chamber, a centrally disposed generally cylindrical member suspended from the dome top and extended through the condensing chamber into the upper part of the arc inclosing chamber said member being provided with openings in its side wall adjacent its top and with a passage therethrough for directing combustion products to the condensing chamber, a diverter of inverted cone-frustum shape projected into said member for deflecting outwardly combustion products to the condensing chamber top, a carbon holder suspended from said member and means for detachably coupling together the condensing chamber parts.

6. In an attachment of the class described, a separable condensing chamber the top of which consists of a continuous dome-like opaque structure and the bottom of which consists of an annular translucent structure terminating in a central depending bulbous arc inclosing chamber, a top plate removably carried upon the dome top and forming means for detachably connecting said attachment to an arc lamp, said dome and top plate being centrally apertured and means for detachably coupling together said condensing chamber parts.

7. In an attachment of the class described, a separable condensing chamber the top of which consists of a continuous dome-like opaque structure, centrally apertured and the bottom thereof consists of an annular dished translucent condensation products receiving structure terminating in a central depending arc inclosing chamber, a centrally disposed generally cylindrical member suspended within the condensing chamber having openings adjacent its top and having a central passage in communication therewith, the bottom of said member extending concentrically into said arc inclosing chamber closely adjacent the inner walls of said chamber whereby combustion products are caused to pass upwardly through said member to the condensing chamber top for circulation therearound.

In testimony whereof I have hereunto signed my name.

HENRY G. DYER.
